(57) **CLAIM**

The ornamental design for a wine glass with protective case, as shown and described.

DESCRIPTION

FIG. 1 is a perspective view of a wine glass with protective case, in an open configuration, showing our new design;

FIG. 2 is a front view thereof;

FIG. 3 is a front view of the protective case in a closed configuration;

FIG. 4 is a bottom view thereof;

FIG. 5 is a top view thereof; and,

FIG. 6 is a cross-sectional view of the wine glass with protective case for closure of the case with the wine glass therein.

1 Claim, 4 Drawing Sheets
